UNITED STATES PATENT OFFICE

WILBUR G. HUDSON, OF NEWARK, NEW JERSEY

DESIGN FOR A TYPEWRITER-RIBBON CLEANER

Application filed September 24, 1932. Serial No. 45,184. Term of patent 3½ years.

To all whom it may concern:

Be it known that I, WILBUR G. HUDSON, a citizen of the United States, residing at Newark, in the county of Essex and State of New Jersey, have invented a new, original, and ornamental Design for a Typewriter-Ribbon Cleaner, of which the following is a specification, reference being had to the accompanying drawing, forming part thereof,

Figure 1 is a top plan view of the typewriter-ribbon cleaner, showing my new design.

Figure 2 is a side elevational view thereof.

I claim:

The ornamental design for a typewriter-ribbon cleaner, as shown.

WILBUR G. HUDSON,
